UNITED STATES PATENT OFFICE

2,675,565

AUTOMATICALLY FOLDING PLAY YARD

George E. Froelich, Two Rivers, Wis., assignor to
 Hamilton Manufacturing Company, Two
 Rivers, Wis., a corporation of Wisconsin

Application October 30, 1951, Serial No. 253,805

8 Claims. (Cl. 5—99)

1

The present invention relates to infants' play yard constructions and particularly to that type which is collapsible or foldable, so that it may be stored in a relatively small space when not in use. In certain respects the present invention relates to improvements over the play yard shown and described in Landry's Patent No. 2,489,183.

In the play yard of the present invention, the floor is elevated, that is, there are depending legs adjacent the corners of the play yard so that the floor of the play yard is positioned a substantial distance from the floor upon which it is supported, when the play yard is extended to the open position. In the ordinary play yard, the center is without support, and according to the present invention a center leg support is provided which is adapted to automatically come to a stable position when the play yard is opened and automatically folds to an out-of-the-way position when the play yard is closed. The center leg is so constructed and arranged that when the play yard is closed, or folded, it is received within waste space so that additional storage space is not required.

One of the primary objects of the present invention is to provide an improvement in folding play yards wherein the floor is supported at its center when the play yard is open and the leg folds into an out-of-the-way position when the play yard is closed.

A further object of the present invention is to provide an improved play yard in which the folding center leg is automatically moved to a stable supporting position and then latched or locked against the adjacent edge of one of the floor sections when the play yard is open, so that adequate stable support is automatically provided at all times.

Other objects of the invention will become apparent from the following specifications, the drawings relating thereto, and from the claims hereinafter set forth.

In the drawings, in which like numerals are used to designate like parts in the several views throughout:

Figure 1 is a side elevational view of a play yard embodying features of the present invention;

Fig. 2 is a top plan view of the play yard shown in Fig. 1;

Fig. 3 is an enlarged, broken, cross-sectional and elevational view taken substantially along the line 3—3 of Fig. 2;

Fig. 4 is a cross-sectional view through the center of the play yard but showing such play yard in its closed or folded position for storage;

2

Fig. 5 is an elevational view taken substantially in the direction of the arrow 5 of Fig. 4;

Fig. 6 is a view similar to Fig. 2 but showing the play yard in an intermediate position, that is, in a position where the sides are partially folded inwardly;

Fig. 7 is a cross-sectional view taken substantially along the line 7—7 of Fig. 6; and

Fig. 8 is an enlarged cross-sectional view taken substantially along the line 8—8 of Fig. 2.

Referring to the drawings, a play yard or play pen embodying the features of the present invention is illustrated and comprises a pair of rigid opposite side members indicated generally at 1 and 2 and a pair of oppositely disposed intervening collapsible or foldable side members indicated generally at 3 and 4. Each side member 1 and 2 includes an upper rail 5 and a lower rail 6 suitably interconnected by a plurality of vertical bars, in the conventional way.

Each of the rigid side members is provided, at each end thereof, with a vertically extending corner post 7 having a depending portion 8 at the lower end thereof which extends below the lower rail 6 and provides a corner leg at each corner. Casters 9 are preferably mounted on the ends of the depending corner legs 8, in the usual way.

Each of the folding side members 3 and 4 includes upper and lower rail portions 10 and 11, respectively, each formed in two parts of substantially equal length and hinged together at their adjacent edges by a hinge 12. The adjacent ends of the rail portions 10 and 11 abut when the play pen is in its open or extended position. The hinges 12 are secured to the outer faces of the rail sections 10 and 11.

The respective halves of rail sections 10 and 11 are interconnected by vertical bars, in the usual way.

The outer ends of the rail sections 10 and 11 are pivotally connected to the adjacent inside faces of corner posts 7 by means of hinges 13 so that each side member 3 and 4 may be broken or folded inwardly at its center and the two halves thereof folded against the inner faces of their respective opposite sides 1 and 2.

The floor of the play pen of the present invention is preferably constructed as disclosed in the Landry patent referred to above and comprises a pair of main floor elements 14 and 15 which are pivotally connected to their adjacent lower rail 6 of rigid ends 1 and 2 by means of hinges 16 and 17, respectively. Such hinges 55 are so positioned so that sections 14 and 15

may fold upwardly against their respective sides. The main floor sections 14 and 15 are generally triangular in form with adjacent flat edges 18 and 19, respectively, which are adapted to lie adjacent each other when the play pen is open.

Each of the main floor elements 14 and 15 is provided, respectively, with a pair of triangular wing sections 20 and 21, and 22 and 23. The wing sections 20, 21, 22, and 23 are hinged to the adjacent edges of their main sections 14 and 15 by underlying hinges 24.

Each of the wing sections 20, 21, 22, and 23 is pivotally connected to its adjacent bottom rail 11 of the foldable side rails 3 and 4 by means of a hinge 25. The hinge 25 is fixed to the under surface of its sections 20, 21, 22, or 23 in the usual way and the outer wing of the hinge is provided with a longitudinally extending slot 26. A screw 27 with washers 28 and 29 on opposite sides of the outer wing of the hinge 25 is received through the washer and through the slot and into the rail 11. Thus each of the wing sections 20, 21, 22, and 23 is pivotally and slidably connected to its adjacent rail section 11 so that relative sliding is permitted as the wing sections are folded.

It will be observed that the floor of the play pen is disposed at a substantial height above the supporting floor by the depending legs 8 and that the floor sections are all pivotally connected to the adjacent lower rails of the play pen around the periphery of the floor. However, the center of the play pen is unsupported and, according to the present invention, a folding center leg is provided so that the play pen floor is adequately supported when the play pen is open and wherein the leg does not interfere with the closing of the play pen and does not require any more space in the folded position than is normally required. Also, the play pen may be readily folded from its open to closed position by means of a foot actuator 30. Such actuator 30 also serves as a support for a center leg 31 and a support for the adjacent edge of the opposite floor panel in a manner that will be described hereinafter. The member 30 has a foot pad 32 which may be depressed to fold the play yard.

The supporting member 30 is fixed to the under surface of the floor section 15 at substantially its transverse center and extends inwardly toward the adjacent floor section 14. The end of the member 30 projects beyond the free edge 19 so that it projects under the adjacent free edge 18 and serves as a support for floor section 14 and its interconnected wings 20 and 21.

The edge 18 of floor section 14 has a reinforcing angle plate 45, preferably formed of metal, having a portion which underlies the section 14 and having a flange which extends across the free edge 18. The inner end of the arm 30 is curved as indicated at 33 and such projecting end supports the section 14 as stated above; and, as the floor section 15 is raised, the curved end 33 will initiate pivoting action of the section 14 and its adjacent wing sections.

The depending center leg 31 is pivotally connected to the supporting member 30 by means of brackets 34. The brackets 34 are provided on opposite sides of the member 30 and are fixed thereto with the depending portion of the brackets extending along the outer sides of the depending leg 31. The leg 31 is pivotally connected to the brackets by means of a pivot pin 35. A

portion of the upper edge 36 of the leg 31 is straight and abuts against the adjacent surface of the member 30 when the leg is in its supporting position to hold the leg rigid, as shown in Figs. 1 and 3. The right upper edge, viewing Fig. 3, is curved, as indicated at 37, to permit pivoting of the leg 31 with respect to the supporting member 30.

The leg 31 is preferably disposed at an angle to the vertical so that it is connected to section 15 but projects beyond or across the adjacent edge of section 14, thus providing a rigid floor support in the open position. This provides a stable construction, particularly when using a swivel caster as over center thrust does not cause the leg 31 to swing up.

A caster 38 is connected to the under side of the leg 31, in the usual way.

A dual purpose locking or latching means and activating or positioning lever is provided on the leg 31 and comprises an upwardly extending metal latch 40 which is mounted within a slot in the leg 31 and is fixed thereto by means of screws or pins 41. The latch 40 projects above the top of the leg 31 and is movably received within a groove or slot 42 formed in the inner edge of the member 30. The upwardly projecting portion of the latch 40 is curved and seats against the inner complementary curved base of the slot 42, as shown in Fig. 3. The upper end of the latch is received within a slot 43 formed in floor section 15 adjacent free edge 19 and terminates substantially flush with the top surface of the floor sections 14 and 15. The latching edge 44 of the latch 40 thus abuts against the adjacent surface of the reinforcing angle 45 when the floor sections are in their open position, as shown in Fig. 3. Thus the leg 31 is locked against accidental displacement.

When the play pen is folded from its open position, as shown in Fig. 1, to its closed position, shown in Fig. 4, by stepping on the foot pad 32, the floor section 15, together with its wing sections 22 and 23, are caused to pivot about their respective bottom rails. This will cause an inward folding of the sides 3 and 4 and consequently will cause a raising and folding of floor section 15 and wing sections 22 and 23, as above stated. The raising of member 30 will initiate raising of section 14. As section 14 is moved away from latch edge 44, the leg 31 is free to pivot by gravity about pivot pin 35. In its intermediate position, the center leg and the floor elements will assume the position shown in Figs. 6 and 7. Complete folding results in the center leg 31 assuming the position shown in Fig. 4, with the folding sides 3 and 4 folded between the rigid sides 1 and 2 and with the floor sections in the folded position shown. As the play pen is positioned by extending the sides 3 and 4, the center leg 31 will automatically come to a stable and latched position, with the play pen ready for use. As the play pen is opened to the fully open position the member 40 acts as a lever when it is engaged by angle plate 45 to force the leg 31 to its stable supporting position shown in Figs. 1 and 3.

Formal changes may be made in the specific embodiments of the invention described without departing from the spirit of the invention, the scope of which is commensurate with the appended claims.

What is claimed is:

1. A play yard comprising a pair of opposed rigid side members, a pair of inwardly foldable side members interposed between the correspond-

ing ends of the first mentioned pair of side members and pivotally connected thereto to define a rectangular floor area when extended, a pair of bottom sections pivotally secured to the respective rigid side members, depending legs adjacent the corners of said play yard extending below said bottom sections, a center leg pivotally connected to one of said bottom sections and depending therebelow, and a locking and lever element on said pivoted leg engaging the adjacent edge of the other bottom section when said sections are extended to their normal open positions.

2. A play yard comprising a pair of opposed rigid side members, a pair of inwardly foldable side members interposed between the corresponding ends of the first mentioned pair of side members and pivotally connected thereto to define a rectangular floor area when extended, a pair of bottom sections pivotally secured to the respective rigid side members, depending legs adjacent the corners of said play yard extending below said bottom sections, a center leg pivotally connected to the under surface of one of said bottom sections and depending therebelow, and a locking and lever element on said pivoted leg extending upwardly to a position substantially flush with the surface of the bottom section and engaging the adjacent edge of the other bottom section when said sections are being extended to their normal open positions to move the center leg to its supporting position and lock it in position.

3. A play yard comprising a pair of opposed rigid side members, a pair of inwardly foldable side members interposed between the corresponding ends of the first mentioned pair of side members and pivotally connected thereto to define a rectangular floor area when extended, a pair of bottom sections pivotally secured to the respective rigid side members, depending legs adjacent the corners of said play yard extending below said bottom sections, a center leg pivotally connected to the under surface of one of said bottom sections and depending therebelow, said center leg pivoting to a position substantially parallel to said bottom sections when said bottom sections are raised to the closed position of the play yard, and a locking and lever element on said pivoted leg engaging the adjacent edge of the other bottom section when said sections are being extended to their normal open positions.

4. A play yard comprising a pair of opposed rigid side members, a pair of inwardly foldable side members interposed between the corresponding ends of the first mentioned pair of side members and pivotally connected thereto to define a rectangular floor area when extended, a pair of bottom sections pivotally secured to the respective rigid side members, depending legs adjacent the corners of said play yard extending below said bottom sections, a center leg pivotally connected to one of said bottom sections adjacent the free edge thereof and depending therebelow, and a locking and lever element on said pivoted leg and movable therewith engaging the adjacent edge of the other bottom section when said sections are being extended to their normal open positions and to be released from engagement with said edge when said sections are raised to their closed positions.

5. A play yard comprising a pair of opposed rigid side members, a pair of inwardly foldable side members interposed between the corresponding ends of the first mentioned pair of side members and pivotally connected thereto to define a rectangular floor area when extended, a pair of

bottom sections pivotally secured to the respective rigid side members, depending legs adjacent the corners of said play yard extending below said bottom sections, a supporting element connected

5 to the under surface of one of said bottom sections and extending under the adjacent edge of the other bottom section when said sections are extended to their normal open positions to provide a support for said other bottom section, a center leg pivotally connected to said supporting element and depending therebelow, and a locking and lever element on said pivoted leg engaging the adjacent edge of the other bottom section when said sections are being extended to their normal open positions.

6. A play yard comprising a pair of opposed rigid side members, a pair of inwardly foldable side members interposed between the corresponding ends of the first mentioned pair of side members and pivotally connected thereto to define a rectangular floor area when extended, a pair of bottom sections pivotally secured to the respective rigid side members, depending legs adjacent the corners of said play yard extending below said bottom sections, a supporting element fixed to the under surface of one of said bottom sections for movement therewith and extending under the adjacent edge of the other bottom section when said sections are extended to their normal open positions to provide a support for said other bottom section, a center leg pivotally connected to said supporting element and depending therebelow, and a locking and lever element on said pivoted leg engaging the adjacent edge of the other bottom section when said sections are being extended to their normal open positions.

7. A play yard comprising a pair of opposed rigid side members, a pair of inwardly foldable side members interposed between the corresponding ends of the first mentioned pair of side members and pivotally connected thereto to define a rectangular floor area when extended, a pair of bottom sections pivotally secured to the respective rigid side members, depending legs adjacent the corners of said play yard extending below said bottom sections, a supporting element fixed to the under surface of one of said bottom sections for movement therewith and extending under the adjacent edge of the other bottom section when said sections are extended to their normal open positions to provide a support for said other bottom section, a center leg pivotally connected to said supporting element and depending therebelow, and a locking and lever element on said pivoted leg engaging the adjacent edge of the other bottom section when said sections are extended to their normal open positions, said supporting element being so constructed and positioned as to raise the other bottom section out of engagement with said locking element when said bottom sections are moved to their raised positions.

8. A folding play yard having depending legs adjacent the corners thereof and comprising a pair of opposite ends, a pair of folding sides pivoted to and connecting the opposite ends, and a pair of separate folding floor elements, each of the floor elements comprising a main part pivotally connected to an opposite end and each of a pair of wing parts pivotally connected along an adjacent edge to its adjacent main part and along another edge to a section of the folding sides, whereby the floor as a whole is supported by the four sides of the play yard and the folding

sides are folded by folding motion of the floor elements and vice versa, a center leg pivotally connected to the under side of one of said main parts adjacent the free edge thereof and depending therebelow, said center leg pivoting upon said folding motion of the floor element, and a locking element on said pivoted leg engaging the adjacent edge of the other bottom section when said sections are extended to their normal open positions.
